UNITED STATES PATENT OFFICE.

LUDWIG F. C. HAAS AND ERNEST JEHEBER, OF LANCASTER, PENNSYLVANIA.

MECHANICALLY-OPERATED DRESS-FORM.

1,134,844.

Specification of Letters Patent.

Patented Apr. 6, 1915.

Application filed June 25, 1913. Serial No. 775,830.

To all whom it may concern:

Be it known that we, LUDWIG F. C. HAAS and ERNEST JEHEBER, citizens of the United States, residing at Lancaster, in the county 5 of Lancaster and State of Pennsylvania, have invented certain new and useful Improvements in Mechanically-Operated Dress-Forms, of which the following is a specification.

10 This invention relates to an improved dress form and more particularly to the mechanically operated type wherein means is provided for imparting motion thereto to better display the dress or apparel arranged 15 thereupon.

The primary object of the invention contemplates the provision of means adapted to be employed in connection with a suitable dress form or model whereby a correct imitation 20 of the movement of the human being is imparted to the apparel or dress upon the form, thereby better displaying the fit and appearance of the dress as it would appear upon the wearer.

25 A further object of the invention resides in the provision of a specially devised form particularly adapted for show cases and store windows wherein the form, with the dress or apparel arranged thereupon is 30 moved after the fashion of the human being, thus permitting the observer to determine the advantages and faults of the apparel displayed, the form or model being operated to walk and move mechanically throughout the 35 length of a suitable track way provided therefor.

The above and additional objects are accomplished by such means as are illustrated in their preferred embodiment in the accompanying 40 drawings, described in the following specification and then more particularly pointed out in the claims which are appended hereto and form a part of this application.

45 In describing the invention in detail, reference will be had to the accompanying drawings, wherein like characters denote like or corresponding parts throughout the several views and in which;

50 Figure 1 is a side elevation of the mechanical dress form constructed in accordance with our invention, one of the floor sections and a portion of the device being shown in section, and the dress being shown in dotted lines; Fig. 2 is a section on the line 2-2 of Fig. 1; Fig. 3 is a section on the line 3-3 of

Fig. 1; and, Fig. 4 is a diagrammatic view of the electric circuit.

Referring now to the drawings, wherein is illustrated the preferred form of our invention, the numeral 1 designates the stationary floor of a show case or store window to which are secured the rails 2 from which the electric current necessary to the operation of our device is derived, the said rails 60 being preferably L-shaped in cross section and screwed or otherwise secured as at 3 to a block or strip of suitable insulating material 4 arranged between the base of the said rails and the floor 1. A second or removable 65 floor section 5 is arranged in spaced relation over and above the stationary floor 1, the former having an opening 6 formed therein directly over the rails 2 above mentioned, the said opening permitting the 70 frame of the mechanical dress form comprising our invention, to extend therethrough.

A guide rail 7 is secured in any suitable manner to the floor section 5 within the opening 6 formed therein, the said rail 7 80 supporting the frame work of the dress form in a manner to be hereinafter fully described.

A suitable carriage, designated in its entirety by the numeral 8 is supported by the 85 guide rail 7, through the medium of rollers 9 mounted for rotation thereon, the upper of the rollers engaging the upper edge of the guide rail as is clearly shown in Figs. 1 and 2 of the drawings.

90 An electric motor 10 is mounted upon a platform or projection 11 formed integrally with the carriage 8 for imparting motion to the mechanical structure comprising our invention, the motor deriving its electric 95 current from a pair of contact brushes 10' mounted on an extension 12 of the carriage fitting between the rails, the brushes being directly engageable with the adjacent faces of the respective rails as is clearly shown by 100 the diagrammatic view in Fig. 4 of the drawings. A switch 13 of any suitable type may be employed for the purpose of making and breaking the circuit as occasion demands.

105 A driven shaft 14 projects from the motor 10 and has keyed or otherwise fixedly secured thereto, a gear wheel 15, the said wheel meshing into a second gear wheel 16 mounted upon a shaft 17 extending longitudinally 110 of the carriage frame 8. A worm gear 18 is arranged or mounted centrally upon the

shaft 17 and is adapted to mesh into a large gear wheel 19 which is in turn mounted upon a shaft 20 extending transversely of the shaft 17 and supported through the medium of a cross beam 21 forming a part of the carriage frame. The said gear wheel is provided with a bevel face gear 22 which is adapted to mesh into a bevel pinion 23 mounted upon the lower extremity of a vertically extending shaft 24 journaled within an upright frame portion 25 formed integrally with the carriage 8, the said frame portion terminating at its upper extremity in a head or enlargement 26, the purpose of which will subsequently appear. A smaller gear wheel 27 is mounted upon the transversely extending shaft 20 and is adapted to mesh into teeth 28 formed upon the lower edge of the guide rail 7, this arrangement causing the carriage to move along the said rail according to the rotation of the gear 27.

Rollers 29 are mounted upon the carriage 8, in spaced relation to the rollers 9 above mentioned, the said rollers 29 engaging the lower edge of the guide rail 7, and with the rollers 9 supporting the upright frame portion 25 in the desired manner.

Double crank arms 30 are formed integrally with the vertically extending shaft 24, the said arms working within the head 26 of the upright frame, each having secured thereto a collar 31 to which is pivotally secured as at 32 a link 33, the latter terminating in a knee cap 34 which is adapted to engage the dress or apparel arranged over the form. The means employed for supporting the link 33 in the desired manner comprises an arm 35 carried by the upright frame portion 25 which terminates at its upper extremity in the bifurcated end 36 having a pin 37 extending therethrough, the said pin working within an elongated aperture or slot 38 formed within a second link 39 pivotally secured as at 40 to the extremity of the link 33. By this arrangement, it will be seen that the said link 33 is supported in the desired manner and is permitted to work back and forth according to the movement of the crank arm 30 thereby moving the dress or apparel by reason of its contact with the knee cap 34 in the desired manner, the slot 38 permitting the lever 39 to move vertically during the reciprocation of the lever 33. Likewise pivotally secured to the link 33 as at 40 and depending therefrom is a lever 41, the opposite end of which is pivotally secured as at 42 to a shoe form 43, the toe of which is weighted so as to be normally held in engagement with the upper face of the floor section 5. Another link 44 is pivotally secured as at 45 to the link 33, the last mentioned link being pivotally secured as at 46 to a pair of smaller links 47 and 48, the former being eccentrically and

pivotally secured as at 49 to a wheel 50 65 mounted for rotation upon the carriage frame 8, while the other lever 48 is pivotally secured as at 51 to the shoe form 43. This arrangement of the levers 41, 44, 47 and 48 will actuate the shoe form 43 in the 70 desired manner and will cause the same to move back and forth from beneath the dress or apparel arranged upon the form thereby producing a correct imitation of the movement of the foot when walking. 75

Having described the detail construction of the mechanical dress form, it now remains to set forth in detail the operation thereof.

The motor 10 deriving its power from the rails 2 through the medium of the contact plates or brushes 12, drives the gear 15 which in turn drives the shaft 17, the latter imparting motion to the large gear wheel 19. The rotation of the gear 19 transmits motion to the smaller gear 27, which, by 85 reason of its engagement with the teeth 28 of the guide rail, moves the entire carriage along the said rail according to the rotation of the said gear 27, the rollers 9 supporting the carriage and the upright frame portion 90 25 in the desired manner. The rotation of the bevel gear 22 imparts motion to the vertically extending shaft 24 for turning the crank arms 30 of the device, the movement of the said arms actuating the knee caps 34 95 and the foot forms 43 in the desired manner. The provision of the links 44, 47, and 48 causes the foot form 43 to move back and forth between the edge of the skirt or dress, this being governed by the rotation of the 100 wheels 50 having the lever 47 eccentrically pivoted thereto. Lateral movement of the entire frame with respect to its support is prevented by the contact plates or brushes 12 fitting between the rails 2, while movement 105 in the opposite direction is prevented by reason of the engagement between the guide rail 7 and the rollers 9 and 29 mounted upon the carriage frame 8.

If desired, the track way comprising the 110 guide rail 7 and the contact plates 2 may be made in sections to render the installation of the device less troublesome, the said track way being curved before being placed within the store window or show case in connection with which our device is used.

It will be seen from the above, taken in connection with the accompanying drawings that the former device is moved forwardly by reason of the engagement between the 120 pinion 27 and the teeth 28 of the guide ways 7; that the disposition of the crank arms 30 with respect to one another will alternately move the knee caps 34 and the foot forms 43 as occasion demands; and that further linkage may be provided and operated from the same source for mechanically moving the arms, the head and the eyes of the form or 120

model if so desired, this being left to the discretion of the manufacturer in the practical application of the invention.

In reduction to practice, we have found 5 that the form of our invention, illustrated in the drawings and referred to in the above description, as the preferred embodiment, is the most efficient and practical; yet realizing that the conditions concurrent with the 10 adoption of our device will necessarily vary, we desire to emphasize the fact that various minor changes in details of construction, proportion and arrangement of parts may be resorted to, when required, without sacrificing any of the advantages of our invention, as defined in the appended claims.

Having thus fully described our invention, what we claim as new and desire to secure by Letters Patent is:

20 1. A mechanical display form including a movable carriage, means actuatable to move the carriage, a knee-cap member, a movable foot form, means including an eccentric operable to actuate the foot form, and means 25 rotatable through movement of said first mentioned actuating means to reciprocate the knee-cap, as and for the purpose set forth.

2. A mechanical display form including a 30 movable carriage, means actuatable to move the carriage in a definite path, a knee-cap member, a movable foot form, means operable through movement of the knee-cap member to actuate the foot form, means directing movement of the knee-cap member 35 when actuated, and means including a crank shaft rotatable through movement of said first mentioned actuating means to move the knee-cap member, as and for the purpose 40 set forth.

3. A mechanical display form including a 45 movable carriage, means actuatable to move the carriage, a crank shaft rotatable through movement of said actuating means, a knee-cap member having connection with the crank shaft, means directing movement of the knee-cap member, a movable foot form, and means including an eccentric operable through movement of the knee-cap member 50 to actuate the foot form simultaneously, as and for the purpose set forth.

4. A mechanical display form including a 55 movable carriage, means actuatable to move said carriage, a reciprocatory knee-cap member, a movable foot form, means including an eccentric operable through movement of said knee-cap member to actuate said foot form, and means including a crank shaft rotatable through movement of said first mentioned actuating means to reciprocate said knee-cap, as and for the purpose set forth.

5. A mechanical display form including a 60 movable carriage, means actuatable to move said carriage, a reciprocatory knee-cap mem-

ber, a movable foot form, means including an eccentric connecting the said knee-cap member and the said foot form for operating the latter through movement of the former, and means including a crank shaft rotatable through movement of the said first 70 mentioned actuating means to reciprocate the knee-cap member, as and for the purpose set forth.

6. A mechanical display form including a carrier movable in a definite path, guide 75 means for the carrier during such movement, means actuatable to move said carrier, a reciprocatory knee-cap member, a movable foot form, means actuatable through movement of the said knee-cap member to 80 move the foot form, and means actuatable through operation of the actuating means first above mentioned to reciprocate the said knee-cap member during movement of the carrier, as and for the purpose set forth. 85

7. A mechanical display form including a carrier movable in a definite path, a guide rail for the said carrier, means actuatable to move the said carrier along the said rail, a reciprocatory knee cap member, a movable foot form, links connecting the said knee-cap member and the said foot form for actuating the latter through movement of the former, an eccentric operating in conjunction with the said links to impart to the 95 said foot form an irregular movement, guide means for the said knee-cap member, and means including a crank shaft rotatable through operation of the said first mentioned actuating means to reciprocate the 100 said knee-cap member simultaneously with the advancement of the said carrier along the said rail, as and for the purpose set forth.

8. The combination with a mechanical display form, of a carrier supporting said form, 105 the carrier being movable in a definite path, a guide rail for the carrier, a rack bar extending parallel with the guide rail, operating means mounted on the carrier and engageable with the rack bar, and means 110 mounted on the carrier for driving the operating means to advance the carrier along the rail, as and for the purpose set forth.

9. A device of the character described including a carrier movable in a definite path, 115 a mechanical display form mounted on the carrier, a guide rail for the carrier, one edge of the rail being provided with teeth, rollers mounted on the carrier and engaging the respective edges of the rail, a gear wheel 120 engaging the teeth of the rail, and means mounted on the carrier operating to simultaneously drive the gear to advance the carrier along the rail and to operate the display form during such advancement, as and for 125 the purpose set forth.

10. A mechanical display form including a carrier movable in a definite path, a guide

4.
rail for the carrier, means moving the carrier along the rail, a double crank shaft mounted on the carrier, means rotating the said shaft simultaneously with the advancement of the carrier along the rail, and display form elements actuatable through rotation of said crank shaft, as and for the purpose set forth.

11. A mechanical display forming including a movable carrier, means directing the movement of the carrier, drive means mounted on the carrier for moving it, a crank shaft mounted on the carrier, said drive means operating to rotate the crank shaft, a 15 knee-cap member, means connecting the knee-cap member and the crank shaft for

reciprocating the former, a movable foot form, means including an eccentric operable through movement of the knee-cap member to actuate the foot form, and means 20 connecting the knee-cap member and the carrier to govern movement of the former when reciprocated, as and for the purpose set forth.

In testimony whereof we affix our signatures in presence of two witnesses.
